SHOE AND METHOD OF MANUFACTURING
THE SAMEFrancis L. Brandt, Wakefield, Mass., assignor to
United Shoe Machinery Corporation, Paterson,
N. J., a corporation of New Jersey

Application October 29, 1935, Serial No. 47,284

18 Claims. (Cl. 12—142)

This invention relates to shoemaking and is illustrated as embodied in shoes the heels of which are attached with adhesives, and with reference to methods of attaching the heels to the shoes.

It is common practice to attach wood heels to shoes by nails or screws which are driven from the inside of the shoe after the last has been pulled. While various finishing operations such

10 as securing covering flaps to the breasts of the heels, edge trimming, edge setting and scouring, are being performed, the heel should form an integral part of the shoe, the shoe at this time preferably being on the last in order to maintain 15 the shape of the shoe and to facilitate carrying out the above operations. In order to avoid having to pull the last for the purpose of securing the heel to the shoe by inside nailing and then having to reinsert the last in the shoe, it is customary in the manufacture of the better grades 20 of shoes to secure the heel temporarily by glue to the shoe preparatory to performing the various finishing operations. After the shoe has been substantially completed and the last has been 25 pulled the heel is permanently secured to the shoe by nails or screws.

In order to retain as much as possible of the pressure of the heel against the heel seat of the shoe for the purpose of preventing the shoe materials from springing back while the finishing operations are being performed and to insure that the heel seat shall set in permanently molded position, it is often the practice to use a temporary attaching screw inserted as disclosed in 30 United States Letters Patent No. 1,502,014, granted July 22, 1924 on an application filed in the name of Frederic E. Bertrand.

In attaching the heel to the shoe temporarily by glue the heel is clamped with considerable pressure against the heel seat of the shoe upon the last for a period sufficient to allow the glue to dry. The heels may be temporarily attached to the shoes by the use of a heel-attaching machine of the turret type, for example as disclosed in Letters Patent of the United States No. 1,376,539, granted May 3, 1921 on an application filed in the names of Isabelle Henne and John L. Preo, in which heels are pressed upon the shoes for a substantial period thereby permitting the glue to dry 45 before the shoes are removed from the machine and go forward for subsequent operations.

The results obtained when using the temporary attaching screw have been generally satisfactory. It has been found, however, that when glue alone 50 is relied upon to attach the heels temporarily to

the shoes some of the heels become detached before the heel-attaching nails or permanent screws are inserted. Even though the heels do not become detached, they frequently spring away from their molded positions upon the heel seats of the 5 shoes. Such a condition is unsatisfactory, particularly in the case of Louis heel work in which the heel has a covering flap secured to its breast and is seldom restored to its original position upon the shoe at the time of the permanent attaching 10 operation, with the result that a wrinkle is formed in the flap in the vicinity of the heel-breast line of the shoe.

With the above and other considerations in view and in accordance with a feature of the present invention, I propose to provide a shoe and a heel which is to be attached to the shoe with anchoring means, and to interpose a mass of hot thermoplastic material between the heel and the shoe. The heel is then pressed against the heel 15 seat of the shoe to force the thermoplastic material into interlocking engagement with said anchoring means, pressure of the heel against the shoe being maintained until the thermoplastic material cools and hardens.

When a quantity of thermoplastic adhesive is 20 used to attach the heel to the shoe, the time dwell during which the heel need be held against the heel seat with molding pressure is reduced materially and there is little danger of the heel becoming loose as the operator performs the various 25 finishing operations. When the last has been removed from the shoe the thermoplastic material may, if desired, be supplemented by nails or screws.

Furthermore, by utilizing an undercut or re-entrant cavity in the attaching face of the heel and a similar cavity or other appropriate anchoring means in the heel-seat portion of the shoe, the thermoplastic material may be forced to take 30 the form of a rivet which, after it has set, has such a strength and permanence and such an interlocking engagement with the shoe and heel as will enable it to serve as the entire heel-attaching means. The thermoplastic material, 35 preferably in the form of a plug, is inserted in one of the undercut cavities and the heel is forced with molding pressure against the heel seat while the plug is in moldable condition; the heel being then clamped against the heel seat 40 until the heel seat has become permanently 45 molded and until the thermoplastic material has set. The plug should be of a size to fill both the cavities as well as to fill, so far as practicable, the space included between the attaching face of the 50 55

heel and the heel seat of the shoe, as well as all 5 interstices or voids in the latter. With the above arrangement the heel is effectively secured to the shoe upper by a large rivet of hardened material which may be said to be clenched to the heel and to the heel seat and its respective ends and which is of sufficient strength to serve as the entire heel-attaching means.

In order to provide an exceptionally strong 10 and durable form-retaining heel end structure for the shoe a further feature of the invention resides in the provision of an insole having a fibre reenforcement attached thereto extending to the margin of the heel seat, which reenforcement has a projecting portion which may be embedded in the hardened mass of thermoplastic cement in a manner to hold the overlasted margin of the shoe upper tightly clamped between the reenforcement and the rim of the heel. It 15 is further contemplated that a shank stiffener be locked in the mass of thermoplastic material and this may be done either independently of the above-mentioned reenforcement or by combining the shank stiffener and the reenforcement as a 20 single unit thereby obtaining in a maximum degree the qualities of strength and rigidity which are so desirable in the heel portion of a shoe.

The above and other features of the invention in both its method and shoe structure aspects 25 will be better understood and appreciated from reading the following detailed description thereof in connection with the accompanying drawings, in which

Fig. 1 is a perspective view of a shoe upon a 30 last, the heel-seat portion of the sole of the shoe having been fitted for the reception of a Louis heel;

Fig. 2 shows in perspective a heel with a mass 35 of thermoplastic adhesive applied to its attaching face, and a tool for applying the adhesive to the heel;

Fig. 3 is a perspective view, partly in section, showing the heel of Fig. 2 after it has been forced 40 with molding pressure against the heel seat of the shoe of Fig. 1;

Fig. 4 is a perspective view of a sole having a fibre reenforcement secured thereto;

Fig. 5 shows a covered Cuban heel having an undercut cavity in its attaching face;

Fig. 6 is a perspective view, partly in section, 50 of the heel end of a shoe having a short outsole, an insole such as that illustrated in Fig. 4, and a shank stiffener;

Fig. 7 is a vertical section of the heel illustrated 55 in Fig. 5 and of the heel end of the shoe illustrated in Fig. 6, a plug of moldable thermoplastic adhesive being positioned in the undercut cavity formed in the attaching face of the heel;

Fig. 8 is a perspective view of the heel end of 60 the shoe illustrated in Fig. 7, a plug of thermoplastic adhesive being inserted in a reentrant or undercut cavity formed in the heel seat of the shoe; and

Fig. 9 is a transverse section taken through 65 the heel end of the shoe after the heel has been permanently attached to the shoe.

In the manufacture of the shoe 22, which is 70 illustrated as mounted on a last 24, a pair of heel-breast receiving shoulders 18 (Fig. 1) have been formed upon the sole 20 and the heel-seat portion of the sole has been reduced thereby providing a tongue 26 of suitable shape to be included within the attaching face 28 of a wood heel 30, tacks 32 being employed, in accordance with usual practice, to secure the tongue 26 to

the insole 34 (Fig. 3) of the shoe. During the heel-attaching operation the rim 36 of the attaching face 28 of the heel 30 is forced with molding pressure against the overlasted counter portion 38 of the shoe upper, the rim forming a shallow groove 40 (Fig. 3) in the previously somewhat rounded margin 42 (Fig. 1) of the heel seat of the shoe.

In order to insure that the heel 30 may be effectively secured to the shoe 22 while various 10 finishing operations are being performed upon the shoe and until the last 24 has been pulled and the heel has been nailed or otherwise permanently attached to the shoe, I propose to interpose a substantial quantity of thermoplastic 15 adhesive 44 between the heel 30 and the heel seat of the shoe 22, the heel then being forced with molding pressure against the heel seat of the shoe and being clamped in molding relation with the heel seat for a period of sufficient duration 20 to insure the setting of the adhesive.

The thermoplastic adhesive 44 may conveniently be applied to the attaching face 28 of the heel 30 by a plate 46 of suitable shape. Although the thermoplastic adhesive 44 is illustrated with 25 reference to its application to the heel, it will be understood that the adhesive may be applied instead to the heel seat of the shoe, or to both. The adhesive 44 is preheated to insure that the same shall be readily moldable under pressure 30 of the heel. During the heel-attaching operation the adhesive 44 fills practically all the voids included between the attaching face 28 of the heel 30 and the heel seat of the shoe thereby providing a large area of bonded contact between 35 the heel and the heel seat.

The heel 30 may be effectively forced against the heel seat of the shoe 22 mounted upon a support 48, by a tread clamp 50 and a back clamp 52 constructed and arranged to engage a thick 40 leather apron 54 which covers the rear face of the heel, the shoe being positioned lengthwise relatively to the clamps by a back gage 56. A machine which comprises the above-mentioned 45 elements and which may be advantageously used for clamping heels to shoes, is disclosed in United States Letters Patent No. 2,076,537, granted April 13, 1937 on an application filed in the name of Bazzoni, a covering flap 57, in accordance with a preferred practice, being applied to the breast of 50 the heel by the machine while the heel is held under molding pressure against the shoe. When heels are temporarily attached to shoes by thermoplastic adhesive as above described, there is little, if any, trouble experienced due to the heels 55 becoming loose between temporary and permanent heel-attaching operations.

While it may be impracticable to attempt to fill absolutely all the voids or interstices included 60 between the attaching face of the heel and the heel seat of the shoe, since it is desirable to insure that the thermoplastic adhesive 44 shall not seep from between the rim 36 of the heel 30 and the counter portion of the shoe, nevertheless by using reasonable care and an appropriate 65 quantity of thermoplastic material these spaces may be substantially filled. It will be understood that the heel-seat portions of the soles may be reduced to various shapes, the amount of thermoplastic adhesive used varying in accordance with 70 the shape of the reduced heel seat.

In order permanently to secure heels to shoes by thermoplastic adhesive without the aid of nails or screws, the procedure illustrated in Figs. 4 to 9 may be utilized. In those figures a shoe 75

58 is provided with a Cuban heel 60 which is secured to the shoe by a rivet 62 of hardened thermoplastic adhesive, best shown in Fig. 9. The insole 64 (Fig. 4) of the shoe 58 has a fibre reinforcement 66 adhesively or otherwise secured to it, the reinforcement having a channel 68 for receiving a shank stiffener 70 and a hollow frustoconical projecting portion 72 which is located at the rear end of the channel and may be described as being funnel-shaped with its smaller end projecting from the insole. The attaching face 74 (Fig. 5) of the heel 60 is provided with an undercut conical cavity 76. After the shoe 58 has been lasted the shank stiffener 70 is tacked or otherwise secured to the insole, the stiffener being of suitable shape to fit within the channel 68 of the fibre reinforcement 66 and having a bent rear end 78 which extends into the hollow conical projecting portion 72 of the fibre reinforcement 66. A short outsole 80 provided with a heel-breast receiving shoulder 82 (Figs. 6 and 7) is then attached to the shoe 58. The rivet 62 of thermoplastic adhesive is formed from a lump or plug 84 which, after being heated to the proper moldable temperature, is inserted within the cavity 76 (Fig. 7) of the heel 60. The shoe 58 is then mounted upon the support 48 and the heel 60 is forced, for example by the use of the heel-attaching machine above referred to, against the heel seat of the shoe which may be described as having a reentrant or undercut cavity 86 (Fig. 6). The lump or plug 84 of thermoplastic adhesive may be inserted in the cavity 86 (Fig. 8) of the heel instead of being inserted in the cavity 76 of the heel. The hardened rivet 62 of thermoplastic adhesive fills the undercut or reentrant cavities 76, 86 and also fills a considerable portion, preferably all or substantially all, of the space between the heel seat 40 of the shoe and the attaching face of the heel.

The heel is clamped in molded relation with the shoe for a period sufficient to insure the hardening of the thermoplastic material, the heel thereafter being held securely in its molded position upon the shoe by the rivet 62 of hardened thermoplastic adhesive which may be said to be clenched at opposite ends within the undercut cavities 76, 86. In the illustrated construction the bent rear end 78 of the shank stiffener 70 is preferably embodied within the rivet 62 and in combination with the fibre reinforcement 66 secures the heel to the rear end of the shoe upper and provides an exceptionally strong and durable form-retaining heel end structure for the shoe.

A thermoplastic adhesive which may be effectively used for attaching heels to shoes is disclosed in United States Letters Patent No. 1,945,803, granted February 6, 1934 on an application filed in the name of Myron E. Delaney.

Having described the invention, what I claim as new and desire to secure by Letters Patent of the United States is:

1. The method of attaching heels to shoes which comprises providing a shoe upper which has a reentrant cavity in its heel seat, providing a heel having a reentrant cavity in its attaching face, interposing a quantity of moldable thermoplastic adhesive between said heel seat and said attaching face, clamping the heel under heavy molding pressure against the heel seat while the adhesive is in a moldable condition thereby causing the same to fill said cavities as well as to fill voids included between the attaching face of the heel and the heel seat, and maintaining the

heel clamped to the heel seat for a period sufficient to insure the setting of the adhesive.

2. The method of attaching a heel to a shoe which comprises providing recesses in the heel and the shoe, interposing a mass of self-hardening plastic material in a plastic condition between the heel and the shoe, pressing the heel against the heel seat of the shoe to force the plastic material into said recesses, and permitting the plastic material to harden.

3. The method of attaching a heel to a shoe which comprises providing cavities in the heel and the shoe, interposing a mass of hot thermoplastic material between the heel and the shoe, pressing the heel upon the shoe to force the thermoplastic material into said cavities, and permitting said material to cool and harden.

4. The method of attaching a heel to a shoe which comprises providing the heel and the shoe with anchoring means, interposing a mass of hot thermoplastic material between the heel and the shoe, pressing the heel upon the shoe to force the thermoplastic material into interlocking engagement with said anchoring means, and permitting said material to cool and harden.

5. The method of making a shoe which comprises securing to an insole a heel seat reinforcing element having a projecting portion, lasting an upper and counter over the insole and securing them thereto, attaching an outsole to the shoe leaving the projecting portion of said reinforcing element exposed, providing a heel with an anchoring means, interposing a mass of plastic material between the heel and the heel seat of the shoe, pressing the heel against said heel seat to force the plastic material into interlocking engagement with said anchoring means and the projecting portion of said reinforcing element, and permitting said plastic material to harden.

6. The method of securing a heel having an undercut cavity in its attaching face to a shoe provided with a heel seat having an undercut cavity, comprising inserting a plug of moldable thermoplastic adhesive into one of said cavities, forcing the heel against the heel seat with molding pressure while the plug is moldable to cause said adhesive to fill said cavities and to fill at least a substantial portion of the voids included between said heel seat and said attaching face, and maintaining pressure of the heel against the heel seat until the adhesive has set thereby permanently securing the heel to the shoe.

7. A shoe the heel and heel seat of which have undercut cavities filled with a hardened mass of plastic material which is of sufficient strength to secure the heel permanently to the shoe.

8. A shoe the heel-seat portion of which has an undercut cavity, a heel engaging said heel-seat portion and also having an undercut cavity, said heel being secured to the shoe by a rivet consisting of a hardened mass of thermoplastic material engaged in and substantially filling both of said cavities.

9. A shoe having a heel seat provided with a cavity, a shank stiffener, and a heel engaging said heel seat and having a cavity in its attaching face, the heel being secured to the heel seat by a hardened mass of plastic material interengaging the cavities in the heel and the heel seat and permanently embedding and locking a portion of the stiffener.

10. A shoe having a heel seat containing a reentrant cavity, a heel having a reentrant cavity in its attaching face, a mass of hardened plastic material engaged in said cavities and connecting

- the heel to the shoe, and a shank stiffener the rear end of which extends into the cavity in the heel seat and is embedded and locked in said material.
- 5 11. A shoe the heel end of which comprises an insole, a rigid reenforcing member attached to the lower face of the heel portion of the insole, said member extending substantially to the margin of the heel seat of the shoe and having 10 a hole in its central portion to provide a cavity the bottom of which is formed by the insole, a heel having an attaching face provided with a cavity, a shoe upper having an overlasted margin clamped between the reenforcing member 15 and the heel, and a mass of hardened plastic material interlocked within said cavities and serving to maintain the edge of the heel tightly against the heel seat.
12. A shoe having a heel provided with a cavity 20 in its attaching face, an insole, a reenforcing member which is secured to the lower face of the insole and has an anchoring portion extending toward the heel, and a shank stiffener the rear end of which extends toward the heel, all of the 25 above parts being secured together by a mass of hard thermoplastic material.
13. A shoe having an insole, a fibre reenforcement secured to the lower face of the insole, said reenforcement having a hollow frusto-conical 30 portion the smaller end of which projects from the insole and a heel having an undercut cavity in its attaching face, all of the parts being secured together by a hardened mass of plastic material substantially filling the hollow frusto- 35 conical portion of the reenforcement and the undercut cavity of the heel.
14. A shoe having an insole, a heel the attaching face of which is provided with an undercut
- recess, a fibre reenforcement secured to the lower face of the insole, said reenforcement having a funnel-shaped portion the smaller end of which projects toward the heel, and a short outsole, all of said parts being engaged and secured together by a hardened mass of plastic material.
15. A shoe having a heel provided with an undercut cavity in its attaching face, an insole, a reenforcing member secured to the lower face of the insole and having a funnel-shaped projection the smaller end of which extends toward the heel, a shank stiffener the rear end of which extends toward the heel and into the funnel-shaped projection, all of the above parts being engaged and secured together by a hard mass of 15 thermoplastic material.
16. A step product consisting of a shoe ready to receive a heel, said shoe being provided with a cavity which is included within the heel-seat of the shoe and is limited in depth by the insole 20 of the shoe, and a mass of thermoplastic material in said cavity.
17. A step product consisting of a shoe ready to receive a heel, said shoe being provided with an undercut cavity which is included within the 25 heel seat of the shoe and is limited in depth by the insole of the shoe, and a mass of thermoplastic material in said cavity.
18. An insole for use in the manufacture of 30 shoes having a relatively rigid reenforcement secured to the lower face of its heel-seat portion, the reenforcement having at its lower face a hollow frusto-conical portion the smaller end of which projects from the insole and a channel extending through a portion of said projection and 35 constructed and arranged to receive a shank stiffener.

FRANCIS L. BRANDT.
